UNITED STATES PATENT OFFICE.

WHITFIELD MORETTI, OF MONTAGUE, MASSACHUSETTS, ASSIGNOR TO MILLERS FALLS COMPANY, OF MILLERS FALLS, MASSACHUSETTS, A CORPORATION OF MASSACHUSETTS.

ELECTRIC TOOL.

Application filed June 10, 1925. Serial No. 36,142.

This invention relates to an improved type of portable electric tool.

It is an object to provide a device of this type which will efficiently perform the purposes for which it is intended, and which will also be economically and readily manufactured and easily assembled.

It is a further object to construct an electric tool which will operate at maximum efficiency over long periods of time, and the parts of which will be maintained at a satisfactory temperature during the entire period of operation.

A still further object resides in providing an electric tool the operating mechanism of which will be effectually housed, but in which those parts which should be inspected, renewed or adjusted at comparatively frequent intervals will be readily accessible.

Another object is that of furnishing an electric tool capable of use in numerous different connections, particularly intended to be employed as a drill and which will be compact in construction and light in weight so that it may readily be manipulated by an operator, and in which, furthermore, the control will be arranged with respect to the other mechanism thereof so that the tool may be handled with nicety, and the finished work will accordingly be free from marring and other errors.

With these and further objects in mind, the invention accordingly comprises the features of construction, combination of elements, and arrangement of parts which will be exemplified in the construction herein-after set forth, and the scope of the application of which will be indicated in the claims.

For a fuller understanding of the nature and objects of the invention reference should be had to the following detailed description taken in connection with the accompanying drawings, in which:

Fig. 1 is a plan view of one form of tool embodying the improved construction of the present invention;

Fig. 2 is an end view thereof, and showing one side of the casing detached;

Fig. 3 is a side elevation of the device 50 as shown in the preceding figures;

Fig. 4 is an enlarged sectional side view thereof;

Fig. 5 is a transverse sectional view taken along the lines 5—5 and in the direction 55 of the arrows of Fig. 4;

Fig. 6 is an enlarged fragmentary sectional side view of the trigger and switch mechanism; and

Fig. 7 is a face view of the trigger. 60

In the present embodiment the invention has been shown as a drill which includes a casing having a main body 10, to the forward end of which a gear and spindle head 11 is detachably secured, as, for example, 65 by the use of screws 12. The rear end of the casing is extended to provide an integral head 13 and a handle 14, the latter being in the nature of what is commonly known as a "pistol-grip" and extending 70 substantially in line with the main body 10 of the casing. This handle is hollow and is fitted with a detachable plate 15 so that its interior may be exposed, the plate being extended to provide a head-portion 16 75 complementary to the head 13.

Situated within the interior of the casing and locked relatively thereto is the field 17 of a motor, and an armature 18 is mounted upon a shaft 19, the outer end 80 of which is carried by a bearing 20 housed within a suitable recess formed in the head 11. The inner end of the armature shaft is also carried by a suitable bearing 21, and this bearing may be supported by the head 85 13 by forming the latter with an inwardly-extending collar 22 of ample inner diameter to accommodate both the bearing and a packing member 23, which latter serves to prevent the escape of lubricant from 90 within the chamber provided by the collar. In order to renew the lubricant within this chamber without the necessity of opening up the casing, the latter may be provided with a port communicating with the chamber, the outer end thereof being preferably controlled by a ball-valve 24. It will furthermore be apparent in the present in- 95

stance that the motor brushes 25 are mounted so that their bodies extend into openings formed in the handle-portion 14, it being appreciated that screw-caps 26 may be employed to retain them in position.

In order to control the motor an electric conduit 27 may enter the casing through an opening in the base of the handle-portion 14, and this conduit may be reenforced 10 against acute bending, and also be prevented from relative movement at its point of entry to the casing, by utilizing a tube 28 of resilient material enclosing the conduit at this point and for a short distance 15 beyond the handle, and employing a clamping-member 29 in association with the casing and bearing against this tube. The inner edge of that portion of the handle 14 which extends at substantially right-angles 20 to the body of the casing is formed with an opening or slot 30 at its upper end, and extending through and beyond this opening is a trigger-member, which may embrace a shank 31 substantially U-shaped in cross section 25 in order to rigidify the same. The upper end of this shank, as in Fig. 6, may terminate in a hook 32 bearing against a trigger stop member 33, the trigger being 30 rockingly supported by bearing against the upper edge of the switch casing 34 at a point adjacent the juncture of its hook and shank, and its inner face being engaged by a switch-moving member 35 so as to normally retain it in the position illustrated 35 in the several views.

The switch assembly will not be described in detail, but one of the leads of the cable 27, in the present instance, is connected directly with one of the brushes 25 40 of the motor, while the second lead is arranged in series with this switch and connected with the second motor brush.

With reference to the head 11 it will be observed that the same has an interior contour 45 best adapted for the accommodation of the outer end of the armature shaft 19, the spindle or chuck-shaft 36 and a countershaft 37. Secured to the first of these shafts is a gear 38 meshing with a comparatively 50 large gear 39 secured to the countershaft 37,—this shaft also mounting a comparatively small gear 40, in turn meshing with a gear 41 of relatively large size secured to the spindle or chuck-shaft 36. 55 Thus, a reduction train is furnished which will increase the power and slow down the speed developed by the chuck 42 or other element associated with the shaft 36, and this train is so arranged that its components 60 occupy a relatively small amount of space, it being observed that, if desired, a suitable bearing 43 may be carried by the extension 44 of the casing, which latter at this point provides adequate support for 65 the shaft 36.

The interior of the head 11 is preferably packed with lubricant, and in order to prevent the escape of the latter it will be observed that in the present instance a plate 45 is interposed between the outer edge of 70 the main casing body 10 and a shoulder formed adjacent the inner edge of the head. This plate has an opening of ample size to accommodate the armature shaft 19, and obviously serves to prevent the rearward 75 flow of lubricant into the main casing body. To also prevent the rearward flow of this lubricant through the opening furnished for the armature shaft and parts assembled therewith, the latter may carry a disk 46, which is fixedly secured thereto at a point adjacent the rear face of the gear 38 and the forward face of the plate 45 so that the likelihood of the lubricant being forced 80 into the main casing is reduced to a minimum.

In the present instance, in order to cool the motor mechanism a fan 47 may be coupled to the shaft 19 at a point immediately adjacent the rear face of the plate 45, 90 and the casing 10 at this point is formed with a radial series of openings 48 through which the air may be exhausted. In order that the air flow may be most effectual the fan or impeller 47 is mounted within a 95 chamber, one wall of which is formed by the plate 45, and the second wall of which, in the present instance, is formed by a washer 49 which bears against an annular shoulder formed in the inner face of the casing 10 and is retained in this position 100 by means of springs 50 carried by pins 50', which are associated with the plate 45 and of a sufficient resiliency to accomplish the result desired. The head 13, together with the complementary portion 16, is formed with openings 51, through which the air is drawn into the casing 10 so that the cool air will play directly upon the commutator and brushes, and thus, a flow of air may be 105 established with the motor in operation.

It will be appreciated that in use an operator may simply associate a suitable tool with the chuck or other holding device which is attached to the outer end of the shaft 36, and may thereupon bring the tool to a point adjacent the work to be performed. While bringing the drill into proper position the same may be grasped, if desired, merely by the handle, and when the motor is to be started this may be accomplished simply by pressing the trigger. Due to the fact that the handle is situated to the rear of the motor casing and at a slight angle thereto, it will be found that the drill may be accurately guided by the operator's hand, and at any instant the operation of the motor may be discontinued 110 simply by releasing the trigger 31, it being noted that when pressure is applied to the 115 handle the motor will be stopped.

latter, and particularly due to the disposition of the same, this will not result in the tool being thrown out of line with the work. Furthermore, incident to the fact that the

5 tool-shaft, i. e., the shaft 36, is preferably not in line with the axial center of the casing, but is rather adjacent the upper edge of the same, the drill-bit or other tool may be accurately sighted with the work.

10 While working the motor will remain at highest operating efficiency, due to the fact that its temperature is constantly maintained at a substantially normal degree by virtue of the fan, which, particularly due

15 to the fact that it is virtually enclosed within a compartment, serves to draw a maximum amount of cooling air past the operating parts and to discharge the heated air through the openings 48.

20 The leads extending beyond the switch and towards the motor brushes, being enclosed within the conduit provided in the lower portion of the handle, are effectually housed against damage. At this time it is

25 also to be noted that, due to the manner in which the cable 27 is reenforced by the tube 28, the former cannot be subjected to such an acute strain as will be likely to result in its becoming broken. Also, incident to

30 the fact that the tube, and, hence, the cable, is locked in place, no strain will be thrown upon the wires and their connections.

Finally, it will be appreciated that the washer 49, as aforesated, will be maintained 35 in position, incident to the provision of the shoulder within the casing and the springs which urge it into contact with this shoulder when the parts are in their normal assembled positions. At any time it becomes

40 necessary it will be obvious that the switch and brush assembly may be inspected and adjusted by simply removing the cover plate 15, together with the extension 16 thereof, and it is obvious that the brushes 25 may

45 be completely withdrawn if this is desirable. Incident to the reduction drive utilized any starting torque may be overcome even if the drill-bit is in contact with the work to be operated upon; and if at any time it becomes

50 necessary to inspect or renew these gears or other parts of the drill, this may be readily accomplished by simply detaching the head 11 from the casing 10, and if the tool is maintained in substantially vertical

55 position with the handle thereof uppermost, it will be found that the entire armature 18 and associated parts will remain in assembled relationship with the mechanism within the head 11. This latter mechanism

60 may be rendered accessible by simply grasping the armature and moving the head away from the same. By this expedient the plate 45 which is retained against other than rotative movement relatively to the shaft 19 will uncover the gear train, it being observed

that, similarly to the manner in which the shaft 19 is supported by the bearing 21, this shaft likewise is supported by the bearing 20.

70 Thus, among others, the objects specifically aforementioned are accomplished, and since certain changes may be made in the above construction, and different embodiments of the invention could be made, without departing from the scope thereof, it is 75 intended that all matter contained in the above description or shown in the accompanying drawings shall be interpreted as illustrative and not in a limiting sense.

80 It is also to be understood that the following claims are intended to cover all of the generic and specific features of the invention herein described and all statements of the scope of the invention which as a matter of language might be said to fall there- 85 between.

Having described my invention, what I claim as new and desire to secure by Letters Patent is:

1. An electric tool, including a motor-enclosing casing, a hollow handle connected with said casing, and a covering plate for closing one side of said handle and a portion of said casing. 90

2. An electric tool, including a motor-enclosing casing, a hollow handle connected with said casing, a covering plate for closing one side of said handle and a portion of said casing, an electric lead extending into said handle, a motor-controlling switch also 100 within said handle and connected with said lead, the connection between said handle and casing being hollow and receiving said lead. 95

3. An electric tool, including, in combination, a motor-enclosing casing, a brush assembly for said motor positioned at the rear end of said casing, a hollow handle extending from said casing, a motor-controlling switch within said handle, an electric 105 lead extending into said handle and through a hollow member connecting the same with said casing, said lead being connected with said brush assembly, and a covering plate closing an open side of said handle and connecting portion, said plate being provided with a part complementary to a portion of said casing, said part lying at a point adjacent said brush assembly. 110

4. An electric tool, including, in combination, a casing, heads at opposite ends of the same, anti-friction bearings associated with said heads, an armature shaft detachably associated with said bearings, a motor-driven toolshaft, a plurality of gears within 120 one of said heads and connecting said last-named shaft with said armature shaft, a plate segregating said gears from said motor, and a disk associated with said armature shaft and arranged adjacent said plate. 125 130

5. A tool, including a casing formed with intake and outlet openings, a shaft rotatable within said casing, a fan secured to said shaft and in line with said outlet openings, an imperforate plate beside said fan and extending beyond said outlet openings through which said shaft passes, a ring-shaped plate extending inwardly from said casing and positioned between the fan and intake openings, said plates providing a compartment for said fan, a gear casing beyond said first-named plate, said shaft extending into said casing, and a disk connected with said shaft within said latter casing and adjacent the said first-named plate.
- 10 6. A tool, including a casing formed with intake and outlet openings, a shaft rotatable within said casing, a fan secured to said shaft and in line with said outlet openings, an imperforate plate held by said casing in a position adjacent said fan, said plate extending beyond said outlet openings and having an opening through which said shaft passes, a ring-shaped plate positioned on the side of said fan opposite to said imperforate plate and resiliently held against a shoulder in said casing by means of expansion springs acting against said imperforate plate, said plates providing a compartment for said fan, a gear casing beyond said first-named plate, said shaft extending into said casing, and a disc connected with said shaft within said latter casing and adjacent the said shaft opening in the said first-named plate whereby leakage is prevented from said gear casing into said fan compartment.
- 15 7. A tool, including a casing formed with intake and outlet openings, a shaft rotatable within said casing, a fan secured to said shaft and in line with said outlet openings, an imperforate plate held by said casing in a position adjacent said fan, said plate extending beyond said outlet openings and having an opening through which said shaft passes, a ring-shaped plate positioned on the side of said fan opposite to said imperforate plate and resiliently held against a shoulder in said casing by means of expansion springs acting against said imperforate plate, said plates providing a compartment for said fan, a gear casing beyond said first-named plate, said shaft extending into said casing, and a disc connected with said shaft within said latter casing and adjacent the said shaft opening in the said first-named plate whereby leakage is prevented from said gear casing into said fan compartment.
- 20 25 30

into said casing, and a disc connected with said shaft within said latter casing and adjacent the said shaft opening in the said first-named plate whereby leakage is prevented from said gear casing into said fan compartment.

7. A tool, including a casing formed with intake and outlet openings, a shaft rotatable within said casing, a fan secured to said shaft and in line with said outlet openings, an imperforate plate held by said casing in a position adjacent said fan, said plate extending beyond said outlet openings and having an opening through which said shaft passes, a ring-shaped plate positioned on the side of said fan opposite to said imperforate plate and resiliently held against a shoulder in said casing by means of expansion springs acting against said imperforate plate, said plates providing a compartment for said fan, a gear casing beyond said first-named plate, said shaft extending into said casing, and a disc connected with said shaft within said latter casing and adjacent the said shaft opening in the said first-named plate whereby leakage is prevented from said gear casing into said fan compartment.

In testimony whereof I affix my signature.

WHITFIELD MORETTI.
